(57) **CLAIM**

We claim the ornamental design for a charging device for an oral irrigator, as shown and described.

DESCRIPTION

FIG. 1 is a top-front isometric view of a charging device for an oral irrigator showing our new design;

FIG. 2 is a top-rear isometric view of the charging device of FIG. 1.

FIG. 3 is a front elevation view of the charging device of FIG. 1.

FIG. 4 is a rear elevation view of the charging device of FIG. 1.

FIG. 5 is a top plan view of the charging device of FIG. 1.

FIG. 6 is a bottom plan view of the charging device of FIG. 1.

FIG. 7 is a right-side elevation view of the charging device of FIG. 1.

FIG. 8 is a left-side elevation view of the charging device of FIG. 1.

FIG. 9 is a top-front isometric view of a second embodiment of a charging device for an oral irrigator.

FIG. 10 is a top-rear isometric view of the charging device of FIG. 9.

FIG. 11 is a front elevation view of the charging device of FIG. 9.

FIG. 12 is a rear elevation view of the charging device of FIG. 9.

FIG. 13 is a top plan view of the charging device of FIG. 9.

FIG. 14 is a bottom plan view of the charging device of FIG. 9.

FIG. 15 is a right-side elevation view of the charging device of FIG. 9; and,

FIG. 16 is a left-side elevation view of the charging device of FIG. 9.

The broken lines, which define the bounds of the claimed design, form no part of the claimed design.
